US0D1108221S

(12) **United States Design Patent** (10) **Patent No.:** **US D1,108,221 S**
(45) **Date of Patent:** **** Jan. 6, 2026**

(54) **PROTECTOR**

(71) Applicant: **MYMICH CO., LTD.**, Taipei (TW)

(72) Inventor: **Nagaya Mitsue**, Taipei (TW)

(73) Assignee: **MYMICH CO., LTD.**, Taipei (TW)

(**) Term: **15 Years**

(21) Appl. No.: **29/925,065**

(22) Filed: **Jan. 22, 2024**

(51) **LOC (15) Cl.** **07-09**

(52) **U.S. Cl.**

USPC **D7/624.1**

(58) **Field of Classification Search**

(57) **CLAIM**

The ornamental design for a protector, as shown and described.

DESCRIPTION

FIG. 1 is a perspective view of a protector showing the new design;

FIG. 2 is a front view of the protector shown in FIG. 1;

FIG. 3 is a rear view of the protector shown in FIG. 1;

FIG. 4 is a left side view of the protector shown in FIG. 1;

FIG. 5 is a right side view of the protector shown in FIG. 1;

FIG. 6 is a top view of the protector shown in FIG. 1; and,

FIG. 7 is a bottom view of the protector shown in FIG. 1.

1 Claim, 6 Drawing Sheets
